DESIGN FOR WALL-PAPER.

SPECIFICATION forming part of Design No. 22,939, dated November 28, 1893.

Application filed October 21, 1893. Serial No. 488,818. Term of patent 3½ years.

To all whom it may concern:

Be it known that I, MARY G. HATCH, a citizen of the United States, residing at New York, in the county and State of New York, 5 have invented and produced a new and original Design for Wall-Paper, of which the following is a specification.

The design consists of an arrangement of buds and blossoms of the pansy flower scattered in an irregular manner over the surface of the paper as represented in the accompanying drawing. The border or upper portion of the design is formed of groups of the pansy flower placed at regular distances apart and

between said groups of flowers are ornamental 15 panels formed by curved lines or arcs of circles and inclosed in said panels are conventionalized pansy flowers forming ornaments.

What I claim is—

The design for wall paper herein shown and 20 described.

Witness my hand this 14th day of October, 1893.

MARY G. HATCH.
